UNITED STATES PATENT OFFICE.

HENRI JEAN JOSEPH MARIE DE REGNAULD DE BELLESCLIZE, OF PARIS, FRANCE.

RADIO SIGNALING SYSTEM.

Application filed August 29, 1921, Serial No. 496,536, and in France January 22, 1920.

(GRANTED UNDER THE PROVISIONS OF THE ACT OF MARCH 3, 1921, 41 STAT. L., 1813.)

The present invention relates to secret radio telegraphic transmission and the objects of the invention are as follows:

To apply to wireless telegraphy a signaling system based on a principle to be hereinafter set forth and that has been known for fifty years as applied to telegraphy through wires in the Baudot apparatus.

At the sending station, a certain number n of keys are successively and in a certain determined order connected with a rotating distributor so as to make possible the sending of signals by means of these keys.

At the receiving station, there is another rotating distributor which is synchronous with the first mentioned distributor. The receiving distributor connects successively n registering apparatuses with the receiving circuit, and this occurs exactly at the time when this circuit receives the corresponding signals from the sending station.

Due to the selecting operation effected by the distributors, an exact correspondence, two by two, is obtained between the n keys of the sending station and the n registers of the receiving station. In this manner, a signal sent by a certain key is received by a certain register, and only by this register.

A further object of the invention is: To arrange the sending and receiving devices provided in accordance with the above system in such a manner that, the radio-telegraphic signals that are sent out cannot be deciphered by any other station than the desired receiving station.

The invention will be more clearly understood by a brief reference to the Baudot system as applied to a radio-telegraphic installation. After this arrangement has been explained, the modification of the apparatus for insuring the secrecy of the transmission will be readily understood.

In the following description and the accompanying drawings, two arrangements are shown to illustrate the invention. These arrangements differ in the details of the radiotelegraphic transmitting and receiving devices.

Figs. 1, 1^a, 1^b, and 1^c show a radiotelegraphic sending station and a corresponding receiving station constructed in accordance with the principle of the Baudot apparatus.

Figs. 2 and 2^a show the same arrangement modified in a manner to prevent decipher-

ing by other than the desired receiving station.

Figs. 3 and 3^a are front and side views of a device for regulating the synchronism of the sending and receiving apparatus of a secret signaling system, no special signal being necessary for effecting the regulation.

Fig. 4 shows a modified receiving arrangement.

The Baudot system is adapted to a radio-telegraphic system in the following manner:

The important parts of the sending station (Fig. 1) are arranged in the following manner:

The distributor D_1 , L_1 is composed of a plate or cylinder D_1 , the periphery of which is divided into a certain number of segments, 22 in the present case, that are insulated from each other. Twenty of these segments ($n=20$) are connected to a corresponding number of keys divided into groups of five (Fig. 1 shows one of these groups $M_1, \dots, M_5$). By means of this arrangement, four simultaneous telegrams may be sent. Each telegram utilizes the five keys of one and the same group. The two last segments 21 and 22 serve for maintaining the synchronism. The manner in which this is accomplished will be set forth more in detail.

The brush L_1 rotates at a constant speed, and successively connects the 22 segments with a local current source P_1 .

Each group of keys is arranged in a keyboard of five keys that may be manipulated by an operator. The time at the disposal of the operator for the sending of a character is equivalent to the time required for the brush to traverse the other segments. In the present case, this will be 17/22 part of the circumference. When a key is once depressed, it is maintained in this position by means of an electromagnet (not shown) until the wiper passes over the five segments of this group and picks up the signal prepared by the adjustment of the keyboard.

The sending station comprises also an oscillation generator G . By short-circuiting a portion of the self induction coil of the antenna, this generator will alternately send out two waves, one working wave when the contact N is open, and a second normal wave when N is closed. This or any other similar arrangement (e. g. the utilization of two

musical tones by means of the Lepel system) is not absolutely indispensable, but it has certain advantages which will be herein-after set forth.

5 Upon the energization of the electromagnet H_1 , the contact N is opened and the working wave is sent out. The operation of the electromagnet H_2 has exactly the opposite effect. By examining the circuit arrangement it will be seen that the electromagnet H_1 is energized when the wiper L_1 engages a segment connected with a key actuated by the operator. The electromagnet H_2 is energized when the wiper engages a segment that is connected with a key in its normal position.

If, for example, the operator desires to send out a signal represented by the combination $M_1 M_3$ normal, $M_2 M_4 M_5$ actuated, while the wiper is passing over the corresponding segments, waves of equal duration will be sent out, and will follow each other in the following combination; normal, working, normal, working, working.

25 The circuits are arranged in such a manner that, when the wiper engages the segment 21, a working wave is sent out, and when it engages segment 22, a normal wave is sent.

30 The receiving station (Fig. 1^a) is arranged in the following manner:

The receiver proper comprises two resonators R_1 and R_2 , that actuate through the agency of indicator relays a common armature J . The resonator R_1 is tuned to the frequency (wave length or musical tone) corresponding to the working wave, and the resonator R_2 is tuned to the frequency corresponding to the normal wave. If the resonators R_1 and R_2 are operated respectively at the normal and working wave length, a detector, preferably, will be utilized in each local circuit, as shown in Figure 1^b. If the resonators R_1 and R_2 are operated at lower frequencies or musical tones, the latter will be obtained in any well known manner; for example, by means of a wave oscillator adapted to give audible beat frequencies in R_1 and R_2 , as shown in Figure 1^c. In this manner, the contact of armature J is closed when the sending station sends out a working wave, and it is open when a normal wave is sent. This differential arrangement may be variously modified, and it is not absolutely essential. However, the arrangement utilizing musical tone frequencies for R_1 and R_2 has great advantages. On one hand, it makes the receiver unresponsive to damped disturbances which affect the resonators R_1 and R_2 in identically the same manner; and on the other hand, it makes possible to increase the sensitiveness and the speed in obviating the necessity of providing a restoring spring for armature J .

65 The distributor $D_2 L_2$ at the receiving

station is like the one provided at the sending station. However, the speed or rotation of wiper L_2 is regulated to a value slightly higher than that of wiper L_1 . If the angular displacement between these two wipers gets to be such that, the wiper L_2 is in engagement with the segment 22' at a time when the wiper L_1 is still in engagement with the segment 21 and causes the sending of a working wave, the electromagnetic regulator B becomes energized (circuit: contact J closed, battery P_2 , wiper L_2 , segment 22', electromagnet B) and, by means of a mechanism not shown in the drawing, slows down the rotation of wiper L_2 of the distributor at the receiving station. In this manner, if the two wipers are out of tune, there is a tendency to establish the synchronism, whereby the two wipers L_1 and L_2 are always in engagement with corresponding segments.

A group of five electromagnetic receivers $E_1 \dots E_5$ shown in Fig. 1^a is provided for each group of five sending keys (e. g. M_1 to M_5). One of these receiving magnets will be energized and caused to attract its armature at the instant the wiper L_2 engages the corresponding segment, whenever the sending station is radiating the working wave. In other words, if the operator at the sending station depresses the corresponding key, one of these magnets will become energized. In this manner, when the wiper L_2 traverses the five segments of the group, the armatures $K_1 \dots K_5$ reproduce the combination determined by the five keys.

The balance of the Baudot apparatus is adaptable to radiotelegraphy without any modification. The operation is as follows:

During the time required for wiper L_2 to traverse the 17 other segments, the armatures of the magnets $K_1 \dots K_5$ remain in the positions they acquired. A translating disc is connected with the wiper L_2 and carries suitably arranged projections and grooves. By means of these projections and grooves, the levers $C_1 \dots C_5$ called also selectors, are actuated and perform movements successively to reproduce all the combinations of the Baudot alphabet. At the moment when the position of the selectors coincides with that of the armatures of the receiving magnets, the printing magnet F becomes energized, and by attracting its armature, presses the paper ribbon against the type-wheel. This wheel is fixedly secured to the wiper L_2 and presents always that character with respect to the paper, the corresponding combination of which is reproduced by the selectors.

In accordance with the present invention, the secrecy of the communications is secured by destroying the regularity or periodicity of the signals by means of which they might be deciphered. Such periodicity

or regularity may be found in the periodicity of the synchronism controlling impulses, in the succession of the signals in the alternating order of the characters in the different telegrams, and in each character the order of the signals of which it is composed.

The arrangements provided in accordance with the present invention for insuring the secrecy are as follows:

10 (a) The synchronism controlling impulses are eliminated. Due to this elimination, it is necessary to control the regulating of the apparatus by means of signals of which the telegrams themselves are composed.

15 This is accomplished in accordance with the following principle:

The instant when the indicator J (Figs. 1^a, 2^a, 3^a) is actuated in response to the attraction by resonators R₁, R₂ is entirely dependent on the position of the wiper L₁ serving the sending distributor, because its movement depends on this wiper. At this same time, the position of wiper L₂ serving the receiving distributor, must be fixed with 20 precision. Thus, through the agency of the movement performed by the indicator J, the relative positions of the two distributors are regulated. If L₂ lags, the indicator J must send to it an advancing impulse, and vice 25 versa.

An embodiment of this principle is illustrated in Figs. 3 and 3^a.

An insulating disc O is rigidly connected with, and is driven by the wiper serving the 35 receiving distributor. Conducting segments are provided on the periphery of this disc. The number of these segments is 2n, double the number of segments provided on the distributor D₂. The segments are insulated from each other, and are alternately connected with two wipers Q₁ and Q₂.

When the indicator J changes its position, a contact V is suddenly pressed against the disc O. The contact is retracted as soon as 45 the indicator J reaches the position opposite to its initial position.

Depending on the common position occupied by the wiper L₂ of the receiving distributor and the disc O, the contact V closes 50 the circuit of battery P₄ either through the agency of wiper Q₁ or through the agency of wiper Q₂.

The other ends of these two wipers are connected with two opposed windings Y₁ and Y₂. One of these windings is provided in a manner to slow down the movement of the wiper L₂ of the distributor, and the other winding to speed up the movement. As shown in Figs. 3 and 3^a, these windings provide an additional energization for the driving motor X of the wiper L₂. When the distributor is slightly lagging and closes e. g. the circuit Y₁, the field of the motor is decreased and its movement accelerated. The 60 additional inductors Y₁ and Y₂ are shunted

by means of large condensers I so as to attenuate the breaking sparks and to increase the quantity of electricity stored in response to the sudden closure of the contact V. If the regulators of the driving motors at the 70 two stations are sensitive and well regulated, the corrections, that are repeated upon each movement of the indicator J, might be very slight.

The contact V may be controlled in a plurality of different ways. Fig. 3^a illustrates an anchor escapement controlling a cam-wheel S, controlled in turn by a spring, not shown.

The positioning of the disc O with relation to the distributor L₂ is determined by means of a preliminary adjustment. This adjustment is made once for all to take into account the angular displacements due to the time constants of the different circuits and 85 the mechanical apparatus.

(b) Elimination of all apparent correspondence between the order in which the n Hertzian signals sent out by the distributor really follow each other, and the order 90 in which these signals ought to arrive to form, for direct reading, the n/5 characters appertaining to n/5 different telegrams.

The distributors D₁, L₁ and D₂, L₂ automatically transmit to each receiving magnet 95 armature the impulse sent out under the control of the corresponding key, and thus it is not necessary to send the signals in the same order in which they will be ready. One of the main features of the present invention is 100 the adaptation of this arrangement to wireless telegraphy. All we need to do is, to connect each key and each receiving magnet armature (Figs. 2 and 2^a) with the shaft of an interrupter having n terminals which in turn 105 are connected with n segments of the corresponding sending or receiving distributor. In accordance with a previous understanding between the operators at the sending and receiving station, any segment may represent 110 a key and a corresponding armature. It should be understood, however, that one and the same segment cannot represent at the same time a plurality of keys or armatures, and each armature must be connected to a 115 segment the order number of which is the same as that of the corresponding key. In order to make possible the operations necessary for the sending and the transcribing, only n+1-n/5 segments (i. e. 30+1-4=17, 120 in the present case) are reserved for each group transmitting or receiving the same telegram. As shown in Fig. 2, the first group might occupy the segments 1, 17 and any other three segments between 1 and 17; and 125 so forth for the other groups.

This arrangement makes impossible the success of any deciphering method, because if a third person intercepts the Hertzian signals, the alphabet may be changed as often 130

as it is desired and the characters of which the telegrams are composed may be arbitrarily mixed up. Furthermore, the momentary stopping of a group of keys is hardly noticeable, and the risk of discovery is lessened.

By setting aside any segment for any key or receiving magnet armature, it becomes necessary to make important modifications 10 in the Baudot apparatus. As a matter of fact, the operator at the sending station, and the transcribing wheel at the receiving station have no more the time necessary for preparing the character to be sent or for 15 transcribing the character received. This disadvantage is remedied in the following manner (Figs. 2 and 2^a):

The sending station comprises a timing device between each key and the corresponding 20 contact. The arrangement is provided in such a manner that, during almost an entire revolution of the distributor (in the present case, exactly 15/20 of a revolution), the keys combined at will do not interfere 25 with a character that is being transmitted, actuate the contacts at the end of the revolution, and cause the sending out of the signal representing the character registered during the revolution that follows. In the following, a detailed description will be given of 30 the mechanism for the group of five keys shown in the drawings and adapted to be connected with terminals 1 to 17.

The electromagnets W are energized while 35 the wiper L₁ traverses the segments 20, 1, 2 . . . , 17. These magnets maintain their contacts in a position determined by the character to be sent. The attracted force of 40 these electromagnets is calculated in such a manner that it always overcomes the springs r_1, r_2 . When engaging segment 3, the wiper L₁ causes the actuation of an audible signal, whereby the operator will be informed that 45 he has to register on the keyboard the next character. The actuated keys cause the armatures T to stick to the electromagnets U, which are energized between segments 3 and 20, inclusive, and the action of which overcoming the action of the springs r_1 and r_2 , 50 maintain the armature in the position into which it has been moved. Due to this movement, the springs are put under tension and they will have a tendency to turn the contact K in a clockwise direction. The keys that 55 are left in their normal position, leave the armature T at a distance from the electromagnet U. The springs r_1 and r_2 are adjusted in such a manner that they will under 60 these circumstances have a tendency to turn the contact K in a counter clockwise direction. When the wiper L₁ engages the terminals 18 and 19, the contacts K are released by the deenergized magnets W and are under 65 the exclusive control of the springs. When the wiper reaches the terminal 20, the

contacts are arrested in their new position. The sending of the signal registered on the keyboard begins now. When the wiper engages the terminals 1 and 2, the electromagnets U release their armatures, and there 70 abut against the keys that are in normal position. And so on and so forth.

An identical arrangement is shown at the receiving station (Fig. 2^a) and operates in the same manner. If the indicator J is actuated by a working signal at the time when the distributor L₂ passes over the corresponding terminal each one of the magnets E₁ . . . E₅ will become energized. The armature T' in question is then attracted and a magnet 80 (U'₁ . . . U'₅) will be energized while the wiper L₂ of the distributor traverses terminals 1 to 19 to maintain the armature in its actuated position. At the end of one revolution, the armatures T' reproduce the combination transmitted by the sending station. While the wiper passes over terminal 18, the magnets W' are deenergized and release the armatures K'₁ . . . K'₅. These armatures in turn reproduce the same combination and are maintained in their position during almost an entire revolution of the distributor, by means of magnets W' which are again energized. While these armatures are thus maintained in their position, the desired 95 character is printed under the control of the selectors and the type-wheel in the same manner as in the usual Baudot apparatus in above explained manner.

This receiving arrangement could be considerably simplified. In each group, the give timing arrangements, the armatures of the receiving magnets, the selectors and the transcribing wheel could be replaced by five electromagnets which impress directly on the 100 type-wheel additional movements which are respectively proportional to 1, 2, 4, 8 and 16.

The circuit arrangement of such system is illustrated in Fig. 4. The give magnets a, b, c, d, e attract armatures, the displacements 110 of which are proportional to 1, 2, 4, 8 and 16. These armatures carry pulleys a₁, b₁, c₁, d₁, e₁. A thread f passes over these pulleys. One end of this thread is attached at g, and the other end is turned around the drum h₁ of 115 the type-wheel h. All the numbers 1 to 31, inclusive, may be obtained by adding 1, 2, 4, 8 and 16 to the combinations. By energizing one or a plurality of the magnets a, b, c, d, e, the type-wheel h may be rotated to an extent in proportion with any of the numbers of the series 1 to 31, i. e. may be operated to impress on the paper any one of the characters carried thereby.

Having now described my invention, what 125 I claim is:

1. In a radio signaling system, the combination of a transmitting system comprising a plurality of groups of keys, the keys of each of said groups being adapted to be 130

- set in accordance with a code for indicating a character, an oscillation generator adapted to radiate impulses of two different frequency characteristics, means for automatically causing said generator to successively radiate either of said impulses in accordance with the position of said keys, means at the receiving station for selectively receiving said impulses, and means for selecting the impulses of each group.
2. In a radio signaling system, the combination of a transmitting system comprising a plurality of groups of keys, the keys of each group being adapted to be differently set in either of two positions in accordance with a code for indicating a character, an oscillation generator adapted to radiate impulses of two different kinds in accordance with the position of said keys, means for predetermining the order in which the impulses are transmitted, means at the receiving station for selectively receiving the two kinds of impulses, and means for selectively indicating the impulses of the groups.
3. In a radio signaling system, the combination of a sending station having a distributor, a rotatable wiper cooperating therewith, a plurality of segments, a plurality of keys connected to said segments and divided into a plurality of equal groups, an oscillation generator adapted to radiate two kinds of impulses depending on the position of each key when the wiper of the distributor passes over the corresponding segment, and a receiving station having a distributor, a wiper adapted to rotate in synchronism with the first mentioned wiper, a plurality of segments and a plurality of electromagnets connected therewith corresponding to the keys and grouped in the same manner.
- 10 impulses of each group.
- 15
- 20
- 25
- 30

2. In a radio signaling system, the combination of a sending station having a distributor, a rotatable wiper cooperating therewith, a plurality of segments, a plurality of keys connected to said segments and divided into a plurality of equal groups, an oscillation generator adapted to radiate two kinds of impulses depending on the position of each key when the wiper of the distributor passes over the corresponding segment, and a receiving station having a distributor, a wiper adapted to rotate in synchronism with the first mentioned wiper, a plurality of segments and a plurality of electromagnets connected therewith corresponding to the keys and grouped in the same manner.

3. In a radio signaling system, the combination of a sending station having a distributor, a rotatable wiper cooperating therewith, a plurality of segments, a plurality of keys connected to said segments and divided into a plurality of equal groups, an oscillation generator adapted to radiate two kinds of impulses depending on the position of each key when the wiper of the distributor passes over the corresponding segment, and a receiving station having a distributor, a wiper adapted to rotate in synchronism with the first mentioned wiper, a plurality of segments and a plurality of electromagnets connected therewith corresponding to the keys and grouped in the same manner, a motor for driving the last mentioned means, and means for controlling the speed of said motor in accordance with the signal impulses received.

HENRI JEAN JOSEPH MARIE
de REGNAULD de BELLESCIZE.
